MAGNETIC SELECTING DEVICE

John C. Sims, Jr., Springhouse, Pa., assignor to Sperry Rand Corporation, New York, N.Y., a corporation of Delaware

Filed Aug. 12, 1955, Ser. No. 528,054

11 Claims. (Cl. 209—74)

This invention relates to magnetic selecting devices and more particularly to devices which perform selecting or control functions magnetically. In the prior art, various devices for performing selecting operations are known, but these have certain drawbacks which are overcome by the present invention which performs its selecting operations through the medium of control portions comprising magnetizable elements which are selectively magnetized and demagnetized.

One object of this invention is to provide a selecting device which is more reliable and accurate than those of the prior art.

Another object of the invention is to provide a simple and inexpensive selecting device.

Still another object of the invention is to provide a selecting device in which the selecting element does mechanical work or mechanically operates the pickup means.

Another object of the invention is to provide an improved card sorting device.

Other objects and advantages of the invention will become apparent as this description proceeds.

In one form, the invention contemplates an endless tape or wheel having a plurality of magnetizable elements along the same. The movement of the wheel is synchronized with the application of magnetizing forces to it so that a selected one or ones of the magnetic elements are magnetized. At a predetermined later time these selected magnetized elements actuate the pickup means. As a result, the pickup means is actuated at predetermined times in accordance with energy fed into the magnetizing circuit. This principle is applied in various ways, as will hereinafter appear in more detail.

In the drawings:

Figure 1 illustrates one form of the invention.

Figure 2 is a cross-sectional view of a part of a pickup wheel and one specific form of pickup head.

Figure 3 is a side view of the device of Figure 2.

Figure 4 illustrates a modified form of selecting wheel along with a modified form of pickup head.

Figure 5 illustrates the device of Figure 4 when the latter is performing a selecting operation.

Figure 6 illustrates another modified form of the invention.

Figure 7 illustrates the device of Figure 6 when the latter is performing a selecting operation.

Figure 8 is an elementary view of a card selecting and storing device.

Figure 9 is a plan view of a sample card used in the system of Figure 8.

Figure 10 is a top view of the system of Figure 8.

Figure 11 is a modified form of the invention wherein the selecting device of Figure 4 is employed to open the door of a card sorting mechanism.

Figure 12 is a side view of a complete card storing system utilizing the parts shown in Figure 11.

In Figure 1, a wheel or non-magnetic disc 10 has a plurality of magnetic elements 11 mounted in the pe-

2

riphery thereof. These elements are of a type which retain their magnetism for at least a few seconds and may be composed of material having a substantially rectangular hysteresis loop, such as a cobalt-nickel alloy or Alnico V. Such devices can be magnetized and retain their magnetism indefinitely, but later may be readily demagnetized by an erasing circuit. Many suitable magnetic materials are known to those skilled in the art. The wheel 10 is driven by a synchronous motor and gear box 12 at a desired speed. The alternating current used for driving the motor is fed through a rectifier 13 and switch 14 to the magnetizing circuit 15 of a stationary electromagnet 16. The latter is in suitable position to magnetize the elements 11. Moreover, the synchronous motor 12 and the position of the elements 11 on the wheel 10 are so related that during each positive half cycle of the low frequency alternating current source, one of the elements 11 is in direct alignment with the magnetic core 16. It follows that if the closing of switch 14 is very accurately timed so that it energizes a particular one of the elements 11 as it passes through the core 16, at a predetermined later time that element will pass the pickup head 17 and energize the latter. Hence, it is possible to accurately delay the effect of the closure of switch 14. 25 The magnetized elements subsequently pass the erasing circuit 18 which demagnetizes them.

Figure 2 illustrates one particular form of pickup head. The wheel 10 has elements 11 therein the same as shown in Figure 1. A stationary yoke 12a of soft iron magnetic material has an armature 13a hinged thereto. If one of the elements 11 was not magnetized by the magnetic core 16, the armature 13a will remain in the position shown when that magnet passes through yoke 12a. In the event that the magnet 11 was magnetized, it will then attract armature 13a as the magnet 11 passes through the yoke 12a. This will rotate the armature about pivot 14a and move the projection 15a against the resilient blade 16a whereupon the blade will move and thus close the contacts 17a of an electric switch.

Figure 4 is another modified form of the invention in which the wheel 10 as a modified shape involving a projection at the trailing edge of each element 11. A substantially vertical member 40 is pivoted at the fixed pivotal point 41 and has hinged or connected thereto, by pivot 43, a horizontal member 42 composed of, for example, soft iron. A stop member 44 is attached to the vertical arm 40 and limits the clockwise motion of member 42 which is biased clockwise by the spring 45. As long as the elements 11 are not energized, the parts 40 to 45 inclusive remain in the position shown. However, if one of the elements 11 (for example magnet 11a) is magnetized and approaches the pickup head 40—45, it attracts the soft iron member 42 downward so that the latter is engaged by the projection 46. This carries the soft iron member 42 away from the stop member 44 and thus rotates the arm 40 as shown in Figure 5. As soon as the wheel 10 has rotated so far that member 42 no longer is held against the projection 46, the member 42 snaps back to its original position as shown in Figure 4. The angular movement of member 40 resulting from the magnetizing of element 11a may be utilized to perform useful work. One example of how this work may be utilized is shown later in connection with Figure 11.

Figure 6 is a modified form of the device of Figure 4 and has a wheel 10 of the same shape as wheel 10 of Figure 4, and having similar projections 46. A non-magnetic arm 60 pivoted at 61 has a soft iron magnetic part 62 hinged thereto about a pivot 63. A spring 64 tends to hold the magnetic part 62 against the arm 60 during normal operation of the system. When none of the elements 11 is magnetized, the part 62 rides clear of the projections 46, and arm 60 is held in this position

by a stop member 65. As shown in Figure 7, if one of the elements 11a of Figure 6 has been magnetized, it will attract magnetic part 62 and rotate it about pivot 63, and, thereby, away from arm 60. The magnetic part 62 will then be caught by a projection 46 and rotated counter-clockwise around pivot 63, thus rotating arm 60 upwards and counter-clockwise around pivot 61. The arm 60 will strike the pin 66, which passes through a hole in the stationary plate 67 and has an enlarged upper part 68 for operating a mechanism and thereby performing useful work. When the projection 46 drives the parts 60 and 62 to the position shown in Figure 7, the pin 66 and the enlarged upper part 68 are driven upward and this upward motion may be utilized to perform a desired control function.

Figures 8 to 10 inclusive show one way in which the invention may be employed to perform useful work in connection with a card sorting machine. The card sorting machine, insofar as shown in Figure 8, is conventional but Figure 10 shows how the invention may be applied thereto. The machine of Figure 8 employs a plurality of rollers 80 for driving the cards from a card supplying mechanism 79 horizontally toward the left at a constant predetermined speed. A pickup device 81 senses the cards and by reason of indicia on the cards, a particular one of the four sorting boxes 82, 83, 84 or 85 is selected. Each of these boxes has a swinging lid which may swing open to the position shown by dotted lines 86. Thus, a card moving along the device will be shunted into the particular sorting box whose door has swung upward to its open position.

Figure 9 illustrates a sample card 90 having one indicium 91 and other spots 92, 93 and 94 where indicia may be applied in place of the one shown at 91. The indicia may be in the form of holes punched in the card, or in the form of a light reflecting spot. In fact, any form of indicia may be employed. As shown in Figure 10, the card 90 moves to a position under the pickup head 81 (see Figure 8). The pickup head comprises four separate head units 100, 101, 102 and 103, each one of which has a sensing mechanism to determine whether or not an indicium is on the card 90 at the position sensed by the particular pickup head in question. For example, the pickup head 100 determines whether or not there is an indicium at point 91. Likewise pickup heads 101, 102 and 103 respectively determine if there are indicia at spots 92, 93 and 94. Generally only one of the four spots on the cards has an indicium and hence only one of the four pickup heads is energized. There are four magnetizing coils 104, 105, 106 and 107 respectively energized by the four pickup heads 100, 101, 102 and 103.

These four coils respectively transmit flux to the smaller magnetizable elements later described, through the medium of magnetic cores 108, 109, 111 and 112. An endless belt 113 has a number of groups of magnetizable elements thereon. Each group of magnetizable elements has four magnetic elements, one for each pickup head 100 to 103. The first group of magnetic elements comprises magnetic elements 114, 115, 116 and 117. The second group comprising magnetic elements 114a, 115a, 116a and 117a is spaced from the first group by a distance equal to that between two of the card sorting boxes, for example the distance between boxes 82 and 83. The other groups of magnetic elements are similarly spaced. These magnetic elements may be composed of any of the materials such as described in connection with the magnetic elements 11 of Figure 1.

Each card sorting box 82, 83, 84 and 85 has a pickup means for sensing whether a particular magnetic element is magnetized and opening the door of the box in event such magnetism is detected. For example, pickup means 118 has a sensing element 119 located a short distance to the left of the present position of magnetic element 114. Pickup head 120 has a sensing element 121 a short

distance to the left of the present position of magnetic element 115a. Pickup means 122 has a sensing element 123 positioned a short distance to the left of the present position of magnetic element 116b, while pickup means 124 has a sensing element 125 located a short distance to the left of the present position of magnetic element 117c.

Assume that when the card 90 of Figure 9 is fed into the device it has an indicium at spot 91. Pickup head 100 will sense this and thus energize coil 104, thus magnetizing magnetic element 114. As the endless belt 113 moves to the left at the same speed that the card moves, the magnetic element 114 will pass under the sensing element 119 and cause the pickup means 118 to open the door of box 82 and thus shunt the card into the box 82 when it arrives at that box. In the event that the spot 92 had the indicium thereon instead of spot 91, the operation would be similar with the exception that now the spot 92 would energize pickup means 101 which would energize coil 105 thus magnetizing element 115. The endless belt would carry magnetic element 115 to the left at the same speed the card moved to the left and when the magnet 115 reached sensing element 121, the pickup means 120 would open the door to box 83 and thus shunt the card 90 into the box 83. If it next be assumed that the indicium was at spot 93 instead of at spot 91, the operation would be as follows. The spot 93 would energize pickup head 102 which would energize coil 106 and thus magnetize magnetic element 116. The magnetized element 116 would travel along with the card until it reached sensing element 123 which would energize pickup means 122 and open the door to box 84 and thus shunt the card into that box. If spot 94 were the one having the indicium thereon, it would energize pickup means 103 which would energize coil 107, magnetizing element 117. The magnetized element 117 would travel to the left slightly ahead of the card until it energized sensing element 125 which would in turn energize the pickup means and open the door to box 85 thus shunting the card into that box. It is noted that there are a plurality of groups of magnetic elements such as 114, 114a, etc. which periodically recur in the proper magnetizing position under the cores 108, 109, 111 and 112 and therefore cards may be fed through the system one after the next, and a new card may be fed into the system each time a new group of magnets arrives under the cores 108 to 112. The erasing head 126 demagnetizes the magnets so that the operation may be repeated.

A card supplying mechanism 79 feeds cards under the pickup means 81 at the proper times. The card supplying means 79 is preferably synchronized with the endless belt 113 so that a card is fed under the pickup device 81 whenever a new row of magnetic elements arrives under the magnetizing means 108 to 112 inclusive. The synchronization of the card feeding means 79 with the belt 113 is not part of the invention and consequently is not illustrated in detail.

Figure 11 shows how the device of Figure 4 may be arranged to open the door of one of the sorting boxes. Identical reference numerals have been applied to identical parts of the apparatus in both figures. The arm 40 is connected by a shaft 150, illustrated by a broken line, to the lid or door 86 of the sorting box 84, for example. Therefore, when an appropriate element 11a is magnetized and attracts armature 42 and thus rotates arm 40, the motion is transmitted through shaft 150 to rotate the door 86 and open the latter. As soon as the magnetized element 11a passes the operative position, the door 86 re-closes due to spring 45a.

Figure 12 shows a card sorting system utilizing the mechanism of Figure 11. In Figure 12 there is a pickup head 81 the same as employed in connection with Figures 8 and 10. This pickup head has four subordinate pickup heads which sense the four spots 91 to 94 inclusive on the card 90 which may be fed into the device. In the event that the spot 91 has an indicium thereon, the

pickup head 81 will energize the wire 160 which in turn will energize coil 161 at the precise time that magnetic element 162 of disc 163 arrives under the coil 161. Thus the magnetic element 162 will be magnetized but none of the other three magnetic elements on the disc 163 will be magnetized. In event the spot 92 has indicium thereon, the pickup head will energize wire 164 and in turn the coil 165 and thus magnetize the magnetic element 166 of the disc 167. None of the other three magnetic elements of this disc will be energized and the apparatus is so timed that the card 90 will arrive under the pickup head 81 at the precise time that magnetic element 166 is facing coil 165. In event spot 93 is the one carrying the indicium, the pickup head 81 will energize wire 168 which will in turn energize coil 169 at the precise time that magnetic element 170 arrives under the coil 169. Magnetic element 170 is carried by the disc 171. In event spot 94 is the one carrying indicia, the pickup head 81 will energize the wire 172 and in turn the coil 173 at the precise time that the magnetic element 174 moves under the coil 173. Magnetic element 174 is carried by the disc 175.

The pickup elements 176 to 179 inclusive are each composed of the parts 40 to 45 inclusive of Figure 11 and each of these units is connected by a suitable shaft such as 150 (of Figure 11) illustrated by dotted lines and designated by reference numbers 150a, 150b, 150c and 150d on Figure 12, to the lids of the boxes 82, 83, 84 and 85 respectively.

The operation of the device of Figure 12 is as follows. In the event that the indicium appears at spot 91 of Figure 9, when the card 90 passes under the pickup head 81, magnetic element 162 will be directly under coil 161 and will be magnetized. The disc 163 will move $\frac{1}{8}$ of a revolution during the same time that the card moves from its starting position to one directly in front of the lid of box 82. The magnet 162 will then actuate the pickup element 176 to open the lid of box 82 and thus shunt the card 90 therein.

In the event that the card has an indicium at spot 92, the magnetic element 166 will be directly under coil 165 at the time that the card 90 passes pickup head 81 and thus magnetic element 166 will be magnetized. This magnetic element will rotate $\frac{3}{8}$ of a revolution in the same length of time that it takes the card 90 to move to a position just to the right of the lid of box 83 at which time the lid will be opened by the magnetic element 166 which actuates the pickup element 177, hence the card 90 will be shunted in the box 83.

Similarly, if the indicium is at spot 93, the magnetic element 170 will be directly under and will be magnetized by coil 169 at the time the latter is energized. The disc 171 will then rotate $\frac{3}{8}$ of a revolution in the same time as is required for the card 90 to move to a position just to the right of the box 84 at which time the magnet 170 will actuate the pickup means 178 and open the door of the box 84, shunting the card therein.

In like manner, if the spot 94 on the card has the indicium thereon, the pickup head will energize coil 173 at the precise time that magnetic element 174 is under that coil, whereupon that magnetic element will be magnetized. The disc 175 will then rotate $\frac{3}{8}$ of a revolution in precisely the time it is required for the card 90 to move to a position just to the right of the lid of box 85, at which time that lid will be opened by the passage of magnet 174 under the pickup means 179. Hence, the card 90 will be shunted into the box 85. Erasing coils 190, 191, 192, and 193 are positioned a fraction of a revolution beyond the pickup means 176 to 179 inclusive and demagnetize the magnets after they have performed their switching operations.

The rollers 80 which propel the cards along the device are synchronized so far as speed is concerned with the rotation of the discs 163, 167, 171 and 175 so that the cards arrive just to the right of the lids of the boxes at

the time that these lids are open. The art has already thoroughly explored and taught means for moving cards along rollers at predetermined speeds and consequently no illustration of such means is deemed to be necessary, it being merely stated that such means is suitably synchronized with the four discs 163, 167, 171 and 175 so that the cards arrive at the proper time for the operations hereinabove set forth. In Figures 8 and 12 the rollers 80 should be spaced from other adjacent rollers by such short distances that the cards will not fall between two rollers unless a lid of a box is open. This spacing is not shown in all cases but those skilled in the art understand that additional rollers and suitable spacings should be employed.

A card feeding mechanism 79 operated by mechanism 180 and driven by motor and gear box 181 may be added if desired. The motor and gear box 181 maintains synchronization between the four discs 163, 167, 171 and 175, and the rollers 80, as well as the card feeding mechanism 79. While the addition of the card feeding mechanism 79 is a desirable expedient, it forms no part of the invention and such means are well known in the art. It is also known how such means may be synchronized with rollers such as 80. Consequently no elaboration of such means is thought necessary; it being noted that so far as the present invention is concerned the card 90 could be slipped under the pickup head 81 manually at the proper instant if desired.

I claim to have invented:

1. In a control system, the combination of an endless movable member having a plurality of spaced elements thereon, said plurality of elements being fabricated of a magnetizable material, magnetizing means located adjacent one point along the path of movement of said endless member, means for selectively energizing said magnetizing means to magnetize selected ones of said magnetizable elements, and pickup means located adjacent another point along the path of movement of said endless member, said endless member further including outwardly extending projections at the trailing edges of the magnetic elements respectively, said pickup means including an armature that is normally carried free of the projections but which is attracted by a magnetized element against the endless member and then moved by the projection trailing such an element.

2. In a control system, an endless movable member having a plurality of spaced elements thereon, said plurality of elements being fabricated of a magnetizable material, magnetizing means located adjacent one point along the path of movement of said endless member, means for selectively energizing said magnetizing means to magnetize selected ones of said magnetizable elements, and pickup means located adjacent another point along the path of movement of said endless member, said endless member including outwardly extending projections on said endless member adjacent the said magnetic elements respectively, said pickup means comprising all of the following: an armature normally located just beyond the path of motion of said projections but being drawn into said path when one of said elements is magnetized, and means for returning the armature to its normal position after the magnetized element has passed the position of said armature.

3. A control system comprising rotatable means having a periphery around which are spaced a plurality of elements of magnetic material, projections extending beyond said periphery at the trailing edges of said elements respectively, magnetizing means located adjacent said periphery for selectively magnetizing said elements, and pickup means spaced along said periphery from the magnetizing means, said pickup means comprising all of the following: a mounting member mounted at and pivoted for rotary movement at one end thereof, an armature pivotally mounted at the other end of said mounting member, means connecting the armature and said mem-

ber to hold the armature in a position generally parallel to a tangent of said periphery and just beyond the path of said projections, said armature having a free end rotatable about its pivot and which is attracted by a magnetized element against the rotatable means and thereupon engaged by the projection trailing said element to thereby rotate the mounting member, and means to be controlled operated by the angular position of the mounting member.

4. A control system as defined in claim 3 in which said mounting member has a normal position generally perpendicular to said tangent, and means normally biasing the armature to a position parallel to said tangent.

5. A control system as defined in claim 3 in which said mounting member is normally substantially parallel to said tangent, and means which holds the armature normally substantially parallel to said tangent.

6. In a control system, a movable member having a plurality of spaced control portions thereon each of which comprises magnetic material, and a plurality of projections, one of said projections located adjacent each of said plurality of control portions, means adjacent the path of movement of said member for magnetizing the material at selected ones of said portions thereby to place predetermined control information on said movable member, mechanical work means adjacent the path of movement of said member, said mechanical work means including a magnetic armature mounted for physical movement toward said member when said armature is magnetically attracted by a magnetized control portion on said member passing adjacent thereto whereby said armature engages a preselected one of said projections on said member and is thereby forced to move, and means for erasing said control portions subsequent to passage of said control portions adjacent said armature.

7. The combination of claim 6 wherein said movable member comprises a plurality of discs mounted for rotation in synchronism with one another, said mechanical work means comprising a plurality of magnetic armatures movably mounted adjacent the peripheries of said discs respectively.

8. The combination of claim 7 wherein said armatures are disposed at different angular locations adjacent the peripheries of said discs respectively.

9. In a system for controlling card sorting, the combination of a plurality of endless movable members having a plurality of spaced information storage elements thereon, each of said plurality of elements being fabricated of a magnetizable material, said endless members including a plurality of outwardly extending projections each located adjacent an edge of one of said magnetic elements, magnetizing means located adjacent said endless members, means for selectively energizing said magnetizing means to magnetize selected ones of said magnetizable elements, said energizing means comprising a card sensing apparatus for deriving information from cards and selectively energizing said magnetizing means according to such information, detecting means located adjacent said endless members, said detecting means including an armature of magnetic material which is normally carried free of said projections but which is attracted by a magnetized one of said elements in motion thereby to be in close proximity to said endless member so that said armature while attracted by said magnetized one of said elements in motion is engaged by and moved by the projection also in motion adjacent such a magnetized element, a plurality of card receiving receptacles into which cards may be placed according to the information thereon, and means for moving cards from said sensing means to said receptacles in synchronous relation with said endless members, each re-

ceptacle having a lid which is linked to and positionally controlled by a separate one of said armatures, said lid being operative to deflect a card into its associated receptacle when said lid is in a certain position.

10. In a card sorting apparatus having a plurality of sorting means each including a device for diverting cards having information thereon into different positions, means for sensing the information on said cards and for producing signals according to said information, and means for moving said cards from said sensing means to said devices in a certain time relationship, said sorting means further including a plurality of endless movable members having a plurality of elements of magnetizable material mounted thereon, means for moving said endless members in synchronism with said means for moving said cards, energizing means for selectively magnetizing said elements according to the signals produced by said sensing means, said diverting devices including a plurality of movable magnetic armatures mounted adjacent said movable members in a one-to-one relationship so that selected ones of said armatures are magnetically attracted and moved toward magnetized ones of said elements in response to the movement of said selectively magnetized elements adjacent said armatures, projections attached to said movable members and located adjacent each of said magnetic elements and extending outwardly from said movable members so as to engage said selected armatures when said armatures are attracted toward said magnetized elements and to move said armatures therewith, and means responsive to the movement of said selected armatures by said projections for actuating associated ones of said diverting devices.

11. In an endless control system, a movable member having a plurality of spaced control portions, each of said control portions comprising magnetizable material, means adjacent the path of movement of said movable member for magnetizing the material at selected ones of said control portions thereby to place predetermined control information on said movable member, mechanical work means adjacent the path of movement of said movable member, said mechanical work means including a magnetic armature which is mounted for movement in a first direction and for movement in a second direction into engagement with said movable member when said armature is magnetically attracted toward a magnetized one of said control portions on said movable member passing adjacent thereto, said movable member including means for engaging said armature and for driving it in said first direction by continued movement of said movable member when said armature is attracted by a magnetized one of said control portions, means for erasing the control information on said control portions subsequent to passage of said control portions adjacent said armature, and utilization means responsive to the movement of said armature in said first direction.
